UNITED STATES PATENT OFFICE

LEE R. HARTLEY, OF FORT WAYNE, INDIANA, ASSIGNOR TO S. F. BOWSER & COMPANY, INC., OF FORT WAYNE, INDIANA, A CORPORATION OF INDIANA

CONTROL AND SIGNAL APPARATUS FOR LIQUID DISPENSERS

Application filed February 12, 1926. Serial No. 87,739.

This invention relates to apparatus for dispensing gasoline or other liquids, and has for its object the provision of signal apparatus for apprising the purchaser of the operating condition of the dispenser and for interlocking the valve mechanism with the signal apparatus and control door.

The invention is exemplified in the combination and arrangement of parts shown in the accompanying drawings and described in the following specification, and it is more particularly pointed out in the appended claims.

In the drawings—

Fig. 1 is a fragmentary elevation, with parts in section, showing one embodiment of the present invention;

Fig. 2 is a section on line 2—2 of Fig. 1;

Fig. 3 is a view similar to Fig. 2 showing the parts in a different position; and

Fig. 4 is an elevation of a dispensing device having the present invention applied thereto.

The numeral 10 designates a post or pedestal liquid dispenser having a container 11 at the top thereof which may be made of glass to permit the liquid within the container to be visible. Suitable pumping apparatus, not shown, is provided for filling the vessel 11

with gasoline or other liquid to be dispensed and a discharge pipe 12 is provided for conducting the liquid to the tank of the automobile. The flow of liquid through the pipe 12 is controlled by a valve 13 having a recess

14 for receiving a suitable operating handle. An overflow pipe 15 extends to the top of the vessel 11 and discharges through a pipe 16 to an underground reservoir. A drain pipe 17 is also connected to the vessel 11 and

is connected to a valve casing 18 having a discharge pipe 19 connected with the underground reservoir. Passage of liquid through the valve casing 18 is controlled by a valve 20 having a valve stem 21 extending outwardly through a packing gland 22. A spring 23 normally closes the valve 20 against its seat

24. Inward pressure on the stem 21 opens the valve 20.

A supporting bracket 25 is connected to corner posts 26 of the pedestal and is provided

with a central opening 27 closed by a swinging door 28. The door 28 is hinged on a pivot pin 29 and is held in its upper closed position by a lock 30. An adjustable contact screw 31 is carried by the door 28 in position to engage a plunger 32 carried in a vertically moving slide 33. A spring 34 normally moves the plunger 32 outwardly. In the position of the slide 33 shown in Fig. 2, the plunger 32 registers with the valve stem 21. When the parts are in the position shown in this figure and the door 28 is closed, the plunger 32 will be moved inwardly by the contact screw 31, thus pressing the valve stem 21 inwardly and opening the valve 20. The slide 33 is connected by a rod 34' to an arm 35 secured to the discharge valve 36. The arm 35 is swung downwardly in the position shown in Fig. 2 to close the valve 36. A second arm 37 is carried by the valve 36 and is connected by a link 38 to an indicator 39. The indicator 39 is pivoted on a stud 40 mounted on the pedestal 10. The indicator 39 projects through a slot 41 in the pedestal casing and is provided with a pointer 42 extending beyond the pedestal casing in position to be seen by the customer. The pointer 42 lies behind and is concealed by a central plate 43 when the indicator is in horizontal position. This is the position the indicator assumes when the arm 35 is turned downwardly, as viewed in Fig. 2, and the valve 36 is closed. When the valve 36 is opened the arm 35 will be raised and the arm 37 will be depressed, as shown in Fig. 3. This will move the pointer 42 to a downwardly inclined position, as shown in Fig. 3, and will indicate to the customer that liquid is being discharged from the tank 11 to the car. To prevent unauthorized discharge of liquid through the valve 36 the door 28 is provided with a stop 44 which lies in the path of a projection 45 on the slide. So long as the door 28 is closed the stop 44 will prevent upward movement of the slide 33 and thus prevent the valve 36 from being opened.

A second indicator 46 is pivoted on the stud 40 and is provided with a rod 47 pivoted at the inner end thereof. The outer end of the indicator 46 is provided with a pointer 48.

which projects through the slot 41 and is arranged in the rear of the pointer 42. The rod 47 is provided with a spring 49 which bears against a lug 50 and tends to swing the pointer 48 downwardly into position behind the center plate 43. A trigger 51 is pivoted on the pivot pin 29 and is provided with bearing discs 52 disposed between adjustable stops 53 on the rod 47. The trigger 51 is provided with a contact nose 54 arranged in the path of the door 28 for swinging the trigger into the position shown in Fig. 2 when the door is closed. This will draw the rod 47 downwardly and raise the pointer 48 to indicate to the customer that the valve is open for returning the liquid to the tank. When the door is open the pointer 48 will be concealed behind the plate 43 and the plunger 32 will move upwardly, as shown in Fig. 3, out of registration with the valve stem 21. The slide 33 will cover the opening in front of the valve stem 21 so that while the door is open it will not be possible to open the valve 20 to permit return of liquid to the supply reservoir. This is an important feature of the invention since it insures against draining liquid to which the customer is entitled, back to the supply reservoir.

It will be seen that the invention provides interlocking mechanism which prevents operation of the discharge valve by unauthorized persons, since this valve is controlled by stop mechanism enclosed within the casing and protected by a door provided with a lock. The interlocking mechanism also prevents draining gasoline to the reservoir when the valve is open for supplying the gasoline to the customer. Connected with the interlocking mechanism is a signal device which apprises the customer of exactly what is taking place.

I claim:

1. Liquid dispensing apparatus comprising a vessel for containing liquid, a conduit for supplying liquid from said vessel, a valve for controlling the flow of liquid through said conduit, a conduit for returning liquid from said vessel to a supply reservoir, a valve for controlling the flow of liquid through said second conduit, a casing for enclosing said valves, a door for closing said casing, a slide disposed adjacent said door, and means on said slide for opening the valve in said return conduit when said door is closed, said means being movable out of operative relation with said valve when said door is open.

2. A dispensing device comprising a vessel for containing liquid, a conduit for supplying liquid from said vessel, a valve for controlling the flow of liquid through said conduit, a conduit for returning liquid from said vessel to a supply reservoir, a valve for controlling liquid through said second conduit, a casing enclosing said last-named valve and having an opening therein, a door for closing said

opening, a movable member interposed between said second-named valve and door, means on said movable member for co-operating with said door to open said second-named valve when said door is closed, and means for shifting said valve operating means out of registration with said second-named valve and into position for preventing operation of said second-named valve when said first-named valve is open.

3. Liquid dispensing apparatus comprising a vessel for containing liquid, a valve for controlling the flow of liquid from said vessel to a supply reservoir, a casing for said valve having an opening therein, a door for closing said opening, a slide interposed between said door and valve, means carried by said slide for operating said valve, and means on said door for actuating said valve operating means when said door is closed, said slide being movable to displace said valve operating means relative to said valve when said door is open, said slide being arranged to prevent access to said valve when so moved.

4. Liquid dispensing apparatus comprising a vessel for containing liquid, a conduit for returning liquid from said vessel to a supply reservoir, a valve for closing said conduit, a casing for said valve having an opening therethrough, a door for closing said casing, means operated by said door for opening said valve when said door is closed, and a signal device operated by said door when said door is closed to indicate that said valve is open.

5. Liquid dispensing apparatus comprising a vessel for containing liquid, a conduit for supplying liquid from said vessel to customers, a valve for closing said conduit, a second conduit for returning liquid from said vessel to a supply reservoir, a valve for closing said second-named conduit, a casing enclosing said second-named valve and having an opening therethrough, a door for closing said casing, a slide arranged in registration with said opening, means carried by said slide for opening said second-named valve when said door is closed, means connecting said slide with said first-named valve, and means co-operating with said slide for locking said first-named valve against operation when said door is closed.

6. A liquid dispensing device comprising a vessel for containing liquid, a conduit for supplying liquid from said vessel, a valve for controlling said conduit, a second conduit for returning liquid from said vessel to a supply reservoir, a valve for controlling said second conduit, a casing enclosing said last-named valve and having an opening therethrough, a door for closing said casing, a slide interposed between said last-named valve and door, a plunger carried by said slide, means on said door for engaging said plunger to open said second valve when said

- door is closed, a signal device operated by said door to indicate that said second-named valve is open when said door is closed, means connecting said first-named valve with said slide, means on said door co-operating with said slide to prevent opening of said first-named valve when said door is closed, and a signal device connected with said first-named valve to indicate when said valve is open. 5
7. In combination a dispensing apparatus having a conduit for delivery liquid purchased by a customer, and mechanically operated signal mechanism associated with said apparatus for indicating to a customer when the passage through said conduit is unobstructed. 10
8. In a dispensing apparatus having a conduit through which liquid purchased by a customer is delivered, the combination of valve mechanism for controlling the passage through said conduit, and mechanically operated signal mechanism controlled by said valve mechanism for indicating to the customer when the passage through said conduit 15 is unobstructed. 25
9. In a dispensing apparatus having a conduit through which liquid purchased by a customer is delivered, the combination of valve mechanism for controlling the passage through said conduit, and mechanically operated signal mechanism controlled by said valve mechanism for indicating to the customer when the passage through said conduit is unobstructed, said signal mechanism comprising a pointer movable from a non-indicating position into an indicating position in response to the operation of said valve mechanism. 30
10. In a dispensing apparatus having a conduit through which liquid purchased by a customer is delivered, a valve for controlling said conduit, a reservoir from which the liquid is drawn, valve mechanism for returning the unpurchased liquid to the reservoir after being drawn therefrom, a pair of signal arms for indicating to the customer the position of the valve mechanism for the delivery conduit and the valve mechanism for the return to the reservoir. 40
11. In a dispensing apparatus having a conduit through which liquid purchased by a customer is delivered, a valve for controlling said conduit, a reservoir from which the liquid is drawn, valve mechanism for returning the unpurchased liquid to the reservoir after being drawn therefrom, a pair of signal arms for indicating to the customer the position of the valve mechanism for the delivery conduit and the valve mechanism for the return to the reservoir, both of said signal arms adapted to occupy a non-indicating position and movable into their respective indicating positions in response to the operation of both of said valve mechanisms. 50
12. Liquid dispensing apparatus comprising a vessel for containing liquid, means for dispensing liquid from said vessel, means for draining liquid from said vessel to a supply reservoir, a pair of indicators, means for moving one of said indicators in one direction when liquid is being dispensed from said vessel, and means for moving the other indicator in the opposite direction when liquid is being drained to said supply reservoir. 55
13. Liquid dispensing apparatus comprising a vessel for containing liquid, a conduit for withdrawing liquid from said vessel, a valve for controlling the flow of liquid through said conduit, a second conduit for returning liquid from said vessel to a supply reservoir, an additional valve for controlling the flow of liquid through said second conduit, interlocking means for preventing simultaneous opening of both of said valves, and two pointers one associated with each of said valves to assume a central position when the valve corresponding thereto is closed, one of said pointers being movable from its central position in one direction when the corresponding valve is opened while the other of said pointers is movable from said central position in the opposite direction when the valve corresponding thereto is opened. 60
14. Liquid dispensing apparatus comprising a vessel for containing liquid, a dispensing conduit connected thereto, a valve for controlling the flow of liquid through said conduit, a second conduit for returning liquid from said vessel to a supply reservoir, another valve for controlling the flow of liquid through said second conduit, an enclosing casing, a door for an opening in said casing, means operative when said first-named valve is closed to effect the opening of said second-named valve when said door is closed, and a signal device for indicating when the first-named valve is open. 65
15. A liquid dispensing device comprising a vessel for containing liquid, a dispensing conduit connected to said vessel, another conduit for draining said vessel, valves for controlling the flow of liquid through said conduits, a casing enclosing said valves, a door for an opening in said casing, means for automatically opening the valve in the drain conduit when said door is closed and said means occupies a predetermined position, and means comprising an abutment on the door for locking the valve in the dispensing conduit in closed position when said door is closed. 70
16. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 75
17. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 80
18. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 85
19. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 90
20. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 95
21. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 100
22. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 105
23. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 110
24. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 115
25. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 120
26. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 125
27. A liquid dispensing device comprising a vessel for containing liquid, a dispensing conduit connected to said vessel, a draining conduit connected to said vessel, valves for controlling the flow of liquid through said conduits, a casing enclosing said valves, means extending to a position outside of said casing for actuating the valve for controlling 130

the flow of fluid in the said dispensing conduit, a door for said casing, means operable by the closure of said door when the dispensing conduit valve is closed for opening 5 the valve in the draining conduit, and means for locking the dispensing conduit valve in closed position when the door is closed and said draining valve is open.

17. Dispensing apparatus comprising a 10 vessel adapted to contain liquid, a dispensing conduit connected thereto, a valve for controlling the flow of liquid through said dispensing conduit, a draining conduit connected to said vessel, a draining valve for controlling the flow of liquid through said draining conduit, means comprising an actuating plunger for opening said draining valve when the plunger is in a predetermined position, a movable support for said plunger, and connections between said movable support and the dispensing valve for holding said plunger in inoperative position except when said dispensing valve is in closed position.

18. Dispensing apparatus comprising a 25 vessel for containing liquid, a dispensing conduit connected thereto, a valve for controlling the flow of liquid through said dispensing conduit, a draining conduit connected to said vessel, a valve controlling the flow of liquid 30 through said draining conduit, a casing for enclosing said valves, a door for said casing, means comprising a plunger for opening said draining valve when the plunger is in a predetermined position, connections between said dispensing valve and said draining valve operating means to hold the plunger out of said predetermined position when the dispensing valve is open, and means on said door in position to actuate said plunger to open said 40 drain valve when the dispensing valve is closed and the door is closed.

19. Dispensing apparatus comprising a vessel for containing liquid, a dispensing conduit connected thereto, a valve for controlling the flow of liquid through said dispensing conduit, a casing for enclosing said valve, means extending to a position outside of said casing for operating said valve, a door for said casing, and means connected between said door and said valve when the door is closed and the said valve is closed for preventing the opening of said valve.

20. In dispensing apparatus, the combination with a dispensing conduit, of a valve for controlling the flow of liquid therethrough, a supply reservoir, means comprising valve mechanism for controlling the return of unpurchased liquid to such supply reservoir, a 55 signal arm, a screen for said signal arm, and connections between said signal arm and said dispensing valve for holding said signal arm concealed by said screen when the dispensing valve is closed and to move said signal arm 60 to a position visible to the customer when

the dispensing valve is open for delivery of liquid through said dispensing conduit.

21. In a dispensing apparatus, the combination with a dispensing conduit, of a valve for controlling the flow of liquid therethrough, 70 a drain conduit, a valve for controlling the flow of liquid through said drain conduit, means for opening said drain valve when the dispensing valve is closed, a pair of signal arms for indicating the position of the valve for the dispensing conduit and the position of the valve for the drain conduit, and connections between said signal arms and the mechanism for operating said valves to operate such signal arms to indicate when the valve in the dispensing conduit is open and to indicate when the valve in the drain conduit is open.

22. In dispensing apparatus, the combination with a dispensing conduit, of a valve for controlling the flow of liquid therethrough, a drain conduit, a casing for enclosing said valves, a door for said casing, means operable by the closure of said door when the dispensing valve is closed for opening the drain valve, a signalling device connected to the dispensing valve to indicate when the latter is open, and another signalling device operable upon the opening of said drain valve by the closure of said door for indicating such opening of the drain valve.

23. Liquid dispensing apparatus comprising a visible measuring vessel, means for controlling the dispensing of liquid from said measuring vessel, a drain valve for controlling the flow of liquid from said measuring vessel to a storage reservoir, and means for giving a visual indication of the flow of the liquid from said measuring vessel to the storage reservoir when said drain valve is open.

24. Dispensing apparatus comprising a measuring tank, means for controlling the dispensing of liquid from said tank, a drain valve for controlling return of liquid from said measuring tank to a supply reservoir, means for opening said drain valve, an indicator, connections between said opening means and said indicator for operating the latter when said drain valve is open to indicate flow of liquid from said measuring tank to said supply reservoir, and a spring for automatically restoring said indicator when said drain valve is closed and said connections are released.

25. In dispensing apparatus, the combination with mechanism for dispensing a liquid, of means for draining such dispensing mechanism into a storage reservoir, mechanism for indicating whether liquid is being dispensed or drained, and interlocking means for preventing draining while liquid is being dispensed.

26. In liquid dispensing apparatus, the combination with dispensing mechanism comprising a measuring tank and a controlling dispensing valve, means for draining the liquid from said measuring tank independently of said valve, interlocking connections between said draining means and said valve to hold the same closed while the liquid is being drained from said tank, and signalling mechanism for indicating the nature of flow from said tank.

27. In dispensing apparatus, the combination with dispensing mechanism comprising a dispensing controlling valve, means for draining liquid from the dispensing mechanism, signalling mechanism for indicating dispensing of the liquid, additional signalling mechanism for indicating draining of the liquid, and interlocking connections between said draining means and said valve for holding the latter closed during the draining of the liquid.

In testimony whereof I have signed my name to this specification on this 9th day of February, A. D. 1926.

LEE R. HARTLEY.
